LAUNDRY BAG HOLDER

Original Filed Nov. 19, 1928

UNITED STATES PATENT OFFICE

OTTO JETEL, OF CHICAGO, ILLINOIS, ASSIGNOR TO JOHN J. RYAN, OF CHICAGO,
ILLINOIS

LAUNDRY-BAG HOLDER

Application filed November 19, 1928, Serial No. 320,283. Renewed June 27, 1930.

This invention relates to a holder for laundry bags and the like, and more particularly to a cabinet holder hinged along one wall for supporting a bag within the cabinet with the mouth of the bag open, and which allows ready removal of a filled bag and replacement with an empty bag, and which cabinet is of such shape and arrangement so that it may be readily placed against a wall or in a corner to occupy minimum floor space without decreasing the capacity of the bag.

An object of the invention is to provide a laundry bag holder which is substantially rectangular in plan, so as to occupy relatively little space without sacrificing capacity.

Another object of the invention is to provide a laundry bag holder, in which a bag is held in open position within a cabinet, which cabinet is hinged along one wall and slit along the opposite wall to enable the cabinet to be opened for the removal of a filled bag.

A further object of the invention is to provide a laundry bag holder of the cabinet type, of two parts with a part hinged so as to completely surround and enclose the bag when the cabinet is closed and to allow removal of the bag when the cabinet is open along its hinged side, together with means for supporting an open mouthed bag within the cabinet.

A still further object of the invention is to provide a laundry bag holder of the cabinet type, which is economical to manufacture, pleasing in appearance, and one which occupies minimum space without sacrificing capacity.

The above, other and further objects of the invention will be apparent from the following description, accompanying drawings, and appended claims.

According to the invention, a cabinet is provided substantially rectangular in plan, and preferably of greater width than depth, and hinged along one of the walls, preferably one of the shorter walls. A clamping

member is secured to one of the other walls of the cabinet for supporting an open mouthed bag within the cabinet, while a cover is hinged to the same other wall for closing the bag when access thereto is not desired, so that a pleasing piece of furniture results and one which may be placed out of the way in a corner or against the wall without sacrificing capacity.

One form of the invention is illustrated in the accompanying drawings, and the views thereof are as follows:

Figure 1 is a perspective view of a cabinet embodying the present invention.

Figure 2 is a vertical central section through a cabinet embodying the invention showing a bag supported within the cabinet and with the cover open.

Figure 3 is a horizontal section taken on line III—III of Figure 2.

Figure 4 is a horizontal section through the cabinet with the parts open and showing a filled bag tied ready for removal.

Figure 5 is a fragmental sectional view taken on line V—V of Figure 2.

The form chosen to illustrate the present invention comprises two parts 1 and 2 hinged at 3, and having a cover 4.

The cabinet illustrated is rectangular in plan, of greater width than depth and with the hinge 3 in one of the shorter walls of the cabinet. The cover 4 is shown as hinged to what will be referred to herein as the rear wall or part 2.

The cabinet is supported on casters 5 so as to be readily movable.

The cabinet is made of any suitable material, such as sheet metal, and may be provided with a pleasing design, such as that shown in Figure 1, or of any other design.

The cabinet has no bottom.

A laundry bag 6 is supported within the cabinet when in closed position, that is, the position shown in the drawings with the exception of Figure 4, by passing the margin

than depth, arranged for hinged opening along one of the shorter walls, a clamping band hinged to the rear wall for holding an open mouthed bag in said cabinet, a cover also hinged to the rear wall for closing the cabinet, the parts comprising the other shorter wall having locking means thereon for locking said cabinet in closed position.

5 In testimony whereof I have hereunto subscribed my name at Chicago, Cook County, 10 Illinois.

OTTO JETEL.
